NOTE COMPANY, OF NEW YORK, N. Y., A CORPORATION OF NEW YORK.

FEEDING MECHANISM FOR ROTARY PRINTING MACHINES.

Application filed February 9, 1922. Serial No. 535,160.

My invention relates to feeding mechanisms for rotary printing machines, and more particularly to a mechanism of this type adapted for use in planographic or similar presses, and having an inclined feed shelf.

In rotary planographic printing presses, particularly those used for producing safety tints upon paper money or other negotiable instruments, dampened sheets of paper are used, while in other classes of work, dry sheets are used. These sheets of paper, in sheets of large dimension, are larger than those ordinarily used in undersurface plates, although the size of the sheet fed to the press is not material. The press with which a feeding mechanism of my invention was particularly designed for use is of large dimensions for presses of this type, and has high speed. The manner of feeding the sheets required their passing along a decline to the printing couple, and in actual practice it was found that there was a tendency of the dampened sheets, by reason of moving inertia and the absence of inherent elasticity because of the moisture therein, to crumple while passing along this incline, in a manner to form creases therein if fed to the printing couple, or to prevent such feeding, and thus cause offsetting upon the impression cylinder. While the same condition was not present with dry sheets, there was a tendency of such sheets to pass too rapidly to the printing couple and thus be improperly fed with relation thereto, with resultant loss of register in succeeding impressions and a high percentage of waste in the planographic press through mutilation of the paper resulting from its improper positioning with relation to the grippers of the printing couple.

The special construction of feeding mechanism herein described is adapted for use in feeding either dry or dampened sheets of paper, not because the conditions of the printing couple would require either dry or dampened sheets, since planographic presses are capable of printing upon both types of paper, but because when subsequent impressions upon the sheet are to be made by un-

dersurface presses, it is necessary to print the safety tint upon dampened sheets so as to secure register with the undersurface impressions, which latter requires the sheets to be so conditioned. If the safety tints were printed upon dry paper, and the paper thereafter wetted before making the undersurface impression, the increase in the size of the sheet due to wetting or the inability to provide for expansion of the sheet from wetting, in proportioning and placing the design upon the planographic plate, would make it impossible to secure that nicety of register which is required with the class of work above referred to. If subsequent impressions are made by means of an offset planographic press, dry sheets are used.

With the above conditions in mind, I have devised a feeding mechanism for rotary planographic presses, (which ordinarily are of the offset type) having front gauge stops and associated mechanisms which will retard the movement of a sheet towards said gauge stops, thus bringing the sheet to rest upon the inclined shelf preparatory to its engagement by the grippers upon one or either of the members of the printing couple. The said stops are so actuated as to be interposed in the path of a sheet advancing towards the printing couple under gravity, by means synchronized with the rotation of the members of the printing couple, which means are also operative upon said stops so as to move them from the path of movement of the sheet substantially simultaneously with the engagement of the sheet by said grippers, and maintain them in this position until the sheet has, in its entirety, passed said stops. The dwell of said sheets while in engagement with said stops will be but momentary, particularly with a high speed press, which will require the rapid advance of succeeding sheets to meet the demands of the printing couple.

I have found, however, particularly with dampened sheets, that even with this slight dwell there is a tendency of the sheets to collapse or crumple with resultant interference in the feeding movement of the sheet under the control of the printing couple, and

sometimes the formation of creases preventing an imperfect impression even in the event that the sheet is fed from the feeding mechanism to the printing couple.

5 To meet this condition, I associate with the front gauge stop structure, a smoothing mechanism which will be brought into engagement with the sheets substantially simultaneously with the withdrawal of the 10 stops, the effect of which will be to remove any surface irregularities resulting from crumpling as the sheet is being drawn from the feeding mechanism, thus causing it, even though it crumple while on the feed shelf, 15 to be fed perfectly flat to the printing couple. This smoothing mechanism is so actuated as to be normally out of the path of the sheet being fed to the front gauge stops, being engaged therewith substantially simultaneously 20 with the withdrawal of said stops from engagement with the front edge of the sheet. The retard mechanism acts upon the sheets before the engagement of the forward edge thereof with the front gauge stops, said 25 mechanism offering a frictional resistance to the passage of the sheets with relation thereto, in their progress toward the stops.

The feed shelf is so constructed as to itself offer slight resistance to the movement 30 of the paper thereover, incidentally directing the edge of the paper toward said retard device.

In a mechanism made in accordance with my invention, I preferably so construct said 35 retard device that its resistance to the passage of the paper may be regulated, thus accommodating the mechanism to different weights or thicknesses of paper.

Various adjustment devices are provided 40 for conforming or adjusting the front gauge stop mechanism to, or in relation to the gripper mechanism upon the member of the printing couple with which it is associated.

The invention consists primarily in a feeding mechanism for rotary printing machines embodying therein an inclined feed shelf section, front gauge stops co-operating therewith, means whereby said stops may be alternately interposed in the path of movement 50 of the sheet upon said shelf, and removed therefrom, and yieldable means adapted to have movement with said stops, whereby when said stops are in the path of movement of a sheet, said yieldable means will operatively engage said feed shelf for checking the movement of said sheet prior to the engagement of the forward edge thereof with said stops; and in such other novel features of construction and combination of parts as 55 are hereinafter set forth and described, and more particularly pointed out in the claims hereto appended.

Referring to the drawings,

Fig. 1 is a sectional view of a feeding 60 mechanism embodying my invention;

Fig. 2 is an isometric view of a portion of said feeding mechanism upon a larger scale; and

Fig. 3 is a front view of the smoothing element and its associated actuating parts.

Like numerals refer to like parts throughout the several views.

In the embodiment of my invention shown in the drawings, 10 indicates a fragmentary portion of the plate cylinder and 11 a portion of the impression cylinder. The cylinder 10 is the ordinary rotary planographic press cylinder adapted to have mounted thereon an offset printing blanket 12, or a plurality of such blankets. The cylinders 10 and 11 are each provided with a gripper mechanism 13 and 14, the former of which, 13, is adapted to receive sheets from the feeding mechanism of my invention and deliver them to the grippers 14 upon the impression cylinder. Mounted adjacent the printing couples 10 and 11 is an inclined shelf 15 adapted to receive sheets of paper from a delivery tape mechanism 16, the sheets being fed to the tapes of said last named mechanism by hand from a feed shelf not shown. The roller 17 is a mere stop gap arranged between the tapes 16 and the inclined shelf 15, so as to prevent the forward edge of the sheet dropping between said tapes and said shelf 15.

The forward edge of the inclined shelf 15 is supported by a rigid metallic fitting or fittings 18, which fittings also carry thin plates 19 having forwardly projecting tongues 20. Co-operating with each of said plates 19 is a front gauge stop 21 having a forked end 22 adapted to straddle the tongue 20 and thus extend across the plane of the upper surface of the plate 19 to avoid any possibility of a sheet passing between said gauge stop and said plate.

The forward end of the plate 19 extends beyond the forward edge of the shelf 15, thus causing the edge of the sheet which is engaged, and rectilinearly positioned, by the downturned forked ends 22 of the stops 21, to project beyond the edge of the shelf 15 in a manner where it can be readily engaged by the gripper mechanism 13 upon the cylinder 10.

The stop gauge arms 21 are carried by and rotatable with a shaft 23, which shaft is adapted to be rocked at intervals which ensure proper timing in the actuation of said stops by the cam and lever mechanism 24 co-operating with the crank arm 25 carried by said shaft 23. Any desired mechanism other than that indicated in the drawings, may be employed, however, a detailed construction of this mechanism being immaterial to the invention.

Carried by each gauge stop 21 is a curved spring 26 projecting downwardly and forwardly in substantial engagement with each

plate 19, said spring being of sufficiently light tension to offer a yielding resistance to the passage of a sheet between it and said plate.

- 5 The tension of the spring 26 is such as to cause it to have a normal tendency to move away from the plate 19, which tendency is overcome by means of an adjustable tension rod 27 having a cross head 28 engaging said 70 spring 26 rearwardly of the forward edge thereof, in a manner to develop that resistance necessary to properly retard the progress of the sheet between said spring and said plate 19. The rod 27 is normally thrust 75 toward the spring 26 by the coiled spring 29 engaging a spring seat 30 upon said rod and a spring seat upon the fitting carrying the stop gauge arm 21. An adjustment nut 31 operates upon screw threads towards the 80 end of said rod to raise it against the tension of the spring 29, a lock nut 32 being employed to avoid loss of adjustment secured through the nut 31.

Any desired number of front gauge stops 25 may be mounted upon the rock shaft, although ordinarily only two such stops are employed upon a press.

The forward edge of the spring 26 is provided with a projecting tongue 33 adapted 30 to enter a notch in the downturned end 22 of the stop 21 so as to permit the establishment and maintenance of the proper relation between said retard spring 26 and the plate 19 without regard to the stop 21.

35 The gauge stops and the retard spring above referred to are for the purpose of properly engaging the forward edge of a sheet advancing upon the shelf 15 for positioning the sheet for longitudinal register, 40 lateral register being secured by other mechanisms and devices which form no part of the present invention.

As stated, however, the sudden stoppage 45 of the paper after its descent by gravity upon the shelf 15 has a tendency to crumple the sheet, to obviate which condition, I provide means which will engage the sheet after the stops are raised to provide clearance for the withdrawal of the sheet from the 50 shelf 15 by the printing couple grippers, and during the feeding of the sheet by the printing couple, which means has a soft yieldable surface which will offer sufficient resistance to the passage of the sheet there-

55 under to remove any folds therein without impeding the sheet in its feeding movement. This means in the form of the invention shown, comprises a laterally extending brush 34 of a width substantially equal to, or 60 greater than, the maximum width of any sheet which the feeding mechanism is capable of handling, mounted upon a rock shaft 35 acted upon by a torsion spring 36 or other means having a normal tendency 65 to raise the bristles of said brush above the

shelf 15 for a sufficient distance to permit the passage of a sheet thereunder, and out of engagement therewith. The bristles of this brush 34 are sufficiently stiff, or sufficiently thick, to smooth down any wrinkles 70 or crumpled portions which may have developed in the sheet, and sufficiently soft to prevent any disturbance in the finish of the surface of the paper, whether wet or dry.

The functionings of said brush are synchronized with those of the front gauge stop and retard mechanism so that with the lowering of said last named mechanism, 75 said brush will be raised, and with the raising of said stop mechanism, said brush will 80 be lowered.

In the form of the invention shown, the actuating mechanism for the brush 34 consists of crank arms 37 and 38 carried by the shaft 35 and extending adjacent the 85 tappets 39 and 40 carried by and movable with the shaft 23.

To regulate the time of the functioning of the brush and for controlling the pressure exerted thereby upon the sheet when 90 the brush is in the operative relation thereto, I mount the tappets 39 and 40 so that they may be adjusted circumferentially of the shaft 23 and provide means whereby they may be set in any adjusted position. 95

In the form of the invention shown, I provide the shaft 23 with fixed collars 41 and 42 having the lugs 43 and 44 thereon respectively, the sleeves 45 and 46 carrying the tappets 39 and 40 being loosely 100 mounted upon the shaft 23 adjacent said collars, and being operatively and adjustably connected therewith by means of adjustment screws passing through the opposite arms of a fork 47 carried by the sleeve 45 105 and bearing against the opposite faces of the lug 43 carried by the collar 41. Said screws are indicated at 48 and 49. The other sleeve 46 is provided with a similar forked portion 50 carrying adjustment screws corresponding with the screws 48-49, engaging 110 the lug 44 upon the collar 42.

To limit the return oscillatory movement of the shaft 35 under the control of the spring 36 I provide said shaft with stop 115 arms 51 and 52 adapted to engage the rock shaft 23 so as to hold the brush 34 in a permanent relation to the shelf 15 and permit a change in the timing of the actuation of said brush through the tappets 39 and 40. 120

The lower end of the shelf 15 is curved adjacent the plate 19 upon an arc of long radius so as to gradually change the direction of movement of the forward edge of the sheet before it engages the front gauge 125 stop and incidently slightly retard the movement of the sheet.

The front gauge stop arm 21 is so mounted upon the shaft 23 as to be capable of adjustment longitudinally of said shaft and 130

also to be capable of adjustment radially thereof or toward and from the printing couple, the former of which adjustments is to accommodate the said stops and their associated mechanisms to sheets of different widths, and the latter of which is to facilitate the assembling of the machine so as to secure the desired co-operating relation of parts without extreme nicety in the dimensions of these mechanisms.

In securing the above adjustments, I provide a split collar 53 enclosing the shaft 23 and having thereon parallel housings 54 and 55 adapted to receive stems 56 and 57 carried by the arm 21.

The stem 56 has a screw-threaded opening therein engaged by the screw 58 by means of which rectilineal movement may be imparted to said arm and its appurtenances 20 in its entirety.

59 indicates a set screw by means of which the adjustment referred to may be made permanent.

The plate 19 is provided with a head 60 mounted upon a slideway 61 upon the bracket 18 so as to permit said plate to be adjusted laterally of the machine to maintain the proper relation of the tongue 20 thereof with the forked downturned end 22 30 of the front gauge stop arm 21.

The operation of the herein described feeding mechanism for rotary printing machines is substantially as follows:—

The sheets to be fed are delivered by hand 35 to the tapes 16, the continual traverse of which will deliver sheets successively to the shelf 15. Since this shelf is inclined toward the meeting point of the members of the printing couple, the rate of movement of the sheet will be accelerated by gravity before it 40 is entirely upon said shelf 15, and there is a tendency for this sheet to acquire considerable momentum before the forward edge thereof reaches a position where it can be engaged by the grippers 13 upon the plate or form cylinder. In fact, the gravity feed 45 of the sheets along the shelf 15 is such a factor that I have found it essential to provide the stop mechanism herein described in order to secure a proper and timely positioning 50 of the forward edge of the sheet to ensure the proper co-operation of the grippers 13 with the delivery movement of the sheet. Between succeeding impressions and while 55 a sheet is being delivered to the shaft 15, the shaft 23 will be so positioned by the cam and lever mechanism 24 that the downturned edge 22 of the front gauge stop arm 21 will be projected across the edge of the plate 19 60 so as to arrest movement of the sheet under gravity upon the shelf 15, and thus prevent overrunning of the sheet with relation to the feed shelf and the gripper mechanism 13, and position the sheet where it will be engaged 65 by said gripper mechanism, irrespec-

tive of any slight variance in the timing of the positioning of the forward edge of the sheet and of the movement of said grippers relative to the plate 19.

The sudden stoppage of the sheet, particularly when damped sheets are used, (and it has been the general practice heretofore to use such sheets when the tint background impression is to be followed by an impression from an undersurface plate) had 70 a tendency to slightly crumple or wrinkle the sheet so that there was a certain loss or wastage from imperfect impressions. The spring tongue 26 is used so as to frictionally engage the sheet before its engagement with 75 the downturned end 22 of the front gauge stop 21 and thus retard the sheet slightly before its engagement with said front gauge stop and check this tendency at least adjacent the forward edge of the sheet. 80 85

The adjustability of the tension of said spring tongue permits regulation of the pressure exerted thereby so as to ensure uniformity in the functioning of the feeding mechanism or its adjustment to sheets of 90 different weight or thickness.

The positioning of the sheet with relation to the front gauge stop will always be just prior to that interval when the grippers 13 reach a position adjacent the plate 19 where 95 they can engage the forward edge of the sheet, and just prior to the movement of the shaft 23 to lift the arm 21 through the control of the cam and lever mechanism 24.

The tongues 20 are used so as to permit 100 the major part of the sheet adjacent the forward edge thereof to project beyond the edge of the plate 19 where it may be readily engaged by the gripper mechanism 13.

While the front gauge stops are positioned in the path of movement of a sheet along the shelf 15, the brush 34 will be elevated with relation to said shelf by the spring 36 acting on the shaft 35, with the crank arms 37 and 38 positioned in the path 110 of movement of the tappets 39 and 40.

Hence, simultaneously with the elevation of the front gauge stops by the oscillation of the shaft 23, the tappets 39 and 40 will, through their engagement with the crank 115 arms 37 and 38, rock the shaft 35 against the tension of the spring 36, and thus force the brush into engagement with a sheet upon the shelf 15 so that as the sheet is thereafter drawn from the shelf 15 by the gripper mechanism 13 in the first instance, and its associated gripper mechanism 14 upon the impression cylinder subsequently thereto, the engagement of said brush with a sheet will have a smoothing action thereon 120 which will take out any wrinkles which may have been formed, without any likelihood of disturbing the position of the sheet with a resultant loss of register. 125

The circumferential adjustment of the 130.

tappets 39 and 40 with relation to the shaft 23 will permit the regulation of the pressure of said brush according to the needs of different qualities of paper, as well as the timing of the actuation of said brush, it being desirable to have the brush 34 engage the sheet substantially simultaneously with, or instantly following, its engagement by the grippers 13.

- 10 The tappets 39 and 40 may be so set as to normally maintain the brush 34 at any desired distance from the shelf 15 and to be constantly engaged with the crank arms 37 and 38 so as to cause the brush to be moved 15 downwardly simultaneously with the initial upward movement of the front gauge stops, or they may be set in a position where they will be normally disengaged from said crank arms so as to cause a very slight delay in the actuation of the brush, although 20 the abrupt rise upon the cam forming a part of the mechanism 24, will afford no substantial dwell under this condition. In fact any variance in the time interval between 25 the actuation of the front gauge stops and the brush is so small as to be negligible, and the adjustability of the tappets 39 and 40 for all practical purposes is merely for the purpose of varying the 30 smoothing friction developed upon the paper by the brush or other smoothing device 34.

The length of the cam forming a part of the mechanism 24 is sufficient to hold the 35 front stop gauges elevated and the brush lowered, until the entire sheet has passed from the shelf 15 under the control of the printing couple, it being understood that the number of said cams upon the plate or 40 form cylinder will coincide with the number of printing surfaces thereon, so as to cause the actuation of the feeding mechanism as each plate approaches the printing position.

45 Immediately following the passage of the rear edge of a sheet from the plate 19 and tongues 20 thereof, the mechanism 24 will restore the shaft 23 to its normal position, thus permitting the spring 36 to impart a 50 return movement to the shaft 35. If by any chance, a sheet upon the shelf 15 should be so close to the preceding sheet as to approach the plate 19 before said preceding sheet has been entirely withdrawn therefrom, the brush or other smoothing device 55 34 will engage this sheet, retard it momentarily and thus afford time for the front stop gauges to be restored to their normal operative position in time to check the advance of the sheet and accurately position the forward edge thereof.

Since buckling of the sheet will not occur until the forward edge thereof meets a fixed non-yielding member, it is apparent 60 that any action of the brush upon the sheet

in the manner immediately above referred to, will not interfere with the bringing of the forward edge thereof into the desired rectilineal position through its engagement with the alined front gauge stops 21—22. 70

The tension of the spring tongue 26 may be varied to secure the desired action of this tongue upon the sheets, the location of the forward edge of said tongue in close proximity to the downturned end 22 of the 75 front gauge stop delaying the development of a braking action upon the sheet until it is in substantial engagement with said stop.

It is to be noted that since the tongue 26 is carried by and movable with the arm 21, 80 it will be elevated with said arm so as to relieve the sheet from any friction therefrom during the feeding movement of the sheet under the control of the printing couple. 85

It is not my intention to limit the invention to the precise details of construction shown in the accompanying drawings, it being apparent that such may be varied without departing from the spirit and scope of 90 the invention.

Having described the invention, what I claim as new and desire to have protected by Letters Patent, is:—

1. A feeding mechanism for rotary printing machines embodying therein an inclined feed shelf section, front gauge stops co-operating therewith, means whereby said stops may be alternately interposed in the path of movement of the sheet upon said shelf, and removed therefrom, yieldable means adapted to have movement with said stops, whereby when said stops are in the path of movement of a sheet, said yieldable means will operatively engage said feed shelf for checking 95 the movement of said sheet prior to the engagement of the forward edge thereof with said stops and a spring-pressed member operative upon said yieldable means and 100 yieldingly forcing them towards said feed shelf. 105

2. A feeding mechanism for rotary printing machines embodying therein an inclined feed shelf section, front gauge stops co-operating therewith, means whereby said 110 stops may be alternately interposed in the path of movement of the sheet upon said shelf, and removed therefrom, retard springs carried by said stops respectively movable therewith, and adapted to operatively engage 115 said feed shelf when said stops are interposed in the path of movement of the sheet, whereby movement of the sheet is checked prior to the engagement of its forward edge with said stops and a spring-pressed member operative upon said retard 120 springs respectively and forcing them towards said feed shelf. 125

3. A feeding mechanism for rotary printing machines embodying therein an inclined 130

- feed shelf section, front gauge stops co-operating therewith, means whereby said stops may be alternately interposed in the path of movement of the sheet upon said shelf, and removed therefrom, retard springs carried by said stops respectively movable therewith and adapted to operatively engage said feed shelf when said stops are interposed in the path of movement of the sheet, whereby movement of the sheet is checked prior to the engagement of its forward edge with said stops, a spring-pressed member carried by each stop and operative upon the retard spring carried thereby and means for varying the operative effect of said spring-pressed member to vary the tension of said retard spring and the resistance afforded thereby to the passage of a sheet between same and the shelf.
4. A feeding mechanism for rotary printing machines embodying therein an inclined feed shelf section, front gauge stops co-operating therewith, means whereby said stops may be alternately interposed in the path of movement of the sheet upon said shelf, and removed therefrom, retard springs carried by said stops respectively, adapted to operatively engage said feed shelf, whereby movement of the sheet is checked prior to the engagement of its forward edge with said stops, means carried by each stop and operative upon the retard spring carried thereby to vary the tension of said spring and the resistance afforded thereby to the passage of a sheet between same and the shelf, said springs being so tensioned as to have normal movement away from the feed shelf, rods carried by stop gauges and forcing said springs toward said shelf, springs acting upon said rods, and means regulating the tension of said last named springs.
5. A feeding mechanism for rotary printing machines embodying therein an inclined feed shelf section, narrow projections extending forwardly of said shelf, front gauge stops each having a downturned forked edge adapted to straddle a projection upon said plates, whereby the forward edge of a sheet is projected beyond said shelf when in engagement with said gauge stops, means whereby said stops may be alternately interposed in the path of movement of the sheet upon said shelf, and removed therefrom, yieldable means adapted to have movement with said stops, whereby when said stops are in the path of movement of a sheet, said yieldable means will operatively engage said feed shelf for checking the movement of said sheet prior to the engagement of the forward edge thereof with said stops and a spring-pressed member operative upon said yieldable means and yieldingly forcing them towards said feed shelf.
6. A feeding mechanism for rotary printing machines embodying therein an inclined feed shelf section, narrow projections extending forwardly of said shelf, front gauge stops each having a downturned forked edge adapted to straddle a projection upon said shelf, whereby the forward edge of a sheet is projected beyond said shelf when in engagement with said gauge stops, means whereby said stops may be alternately interposed in the path of movement of the sheet upon said shelf, and removed therefrom, and retard springs carried by said stops respectively and each having a projecting tongue passing through the downturned forked end of a gauge stop, said springs being adapted to operatively engage said feed shelf when said stops are interposed in the path of movement of a sheet, whereby movement of the sheet is checked prior to the engagement of its forward edge with said stops.
7. A feeding mechanism for rotary printing machines embodying therein an inclined feed shelf section, narrow projections extending forwardly of said shelf, front gauge stops each having a downturned forked edge adapted to straddle a projection upon said shelf, whereby the forward edge of a sheet is projected beyond said shelf when in engagement with said gauge stops, means whereby said stops may be alternately interposed in the path of movement of the sheet upon said shelf, and removed therefrom, retard springs carried by said stops respectively and each having a projecting tongue passing through the downturned forked end of a gauge stop, said springs being adapted to operatively engage said feed shelf when said stops are interposed in the path of movement of a sheet, whereby movement of the sheet is checked prior to the engagement of its forward edge with said stops, and means whereby said gauge stops and the retard springs carried thereby may be adjusted toward or from the forward edge of said feed shelf.
8. A feeding mechanism for rotary printing machines embodying therein an inclined feed shelf section, front gauge stops co-operating therewith, means whereby said stops may be alternately interposed in the path of movement of the sheet upon said shelf, and removed therefrom, and retard springs carried by said stops respectively, adapted to operatively engage said feed shelf, whereby movement of the sheet is checked prior to the engagement of its forward edge with said stops, said feed shelf being curved adjacent its forward edge.
9. A feeding mechanism for rotary printing machines embodying therein an inclined feed shelf section, thin plates projecting forwardly thereof toward the printing couple, projections upon said plates, front gauge stops each having a downturned forked edge adapted to straddle a projection upon said shelf, whereby the forward edge of a sheet is projected beyond said shelf when in engagement with said gauge stops, means whereby said stops may be alternately interposed in the path of movement of the sheet upon said shelf, and removed therefrom, and retard springs carried by said stops respectively, adapted to operatively engage said feed shelf, whereby movement of the sheet is checked prior to the engagement of its forward edge with said stops, and means whereby said gauge stops and the retard springs carried thereby may be adjusted toward or from the forward edge of said feed shelf.

6

- plates, whereby the forward edge of a sheet is projected beyond said shelf when in engagement with said gauge stops, means whereby said stops may be alternately interposed in the path of movement of the sheet upon said shelf, and removed therefrom, yieldable means adapted to have movement with said stops, whereby when said stops are in the path of movement of a sheet; said yieldable means will operatively engage said feed shelf for checking the movement of said sheet prior to the engagement of the forward edge thereof with said stops and a spring-pressed member operative upon said 15 yieldable means and yieldingly forcing them toward said feed shelf.

10. A feeding mechanism for rotary printing machines embodying therein an inclined feed shelf section, front gauge stops co-operating therewith, means whereby said stops may be alternately interposed in the path of movement of the sheet upon said shelf, and removed therefrom, yieldable means adapted to have movement with said 20 stops, whereby when said stops are in the path of movement of a sheet, said yieldable means will operatively engage said feed shelf for checking the movement of said sheet prior to the engagement of the forward edge thereof with said stops, and a smoothing device operative upon the sheet while it is being fed from said feed shelf.

30 11. A feeding mechanism for rotary printing machines embodying therein an inclined feed shelf section, front gauge stops co-operating therewith, means whereby said stops may be alternately interposed in the path of movement of the sheet upon said shelf, and removed therefrom, yieldable means adapted to have movement with said 35 stops, whereby when said stops are in the path of movement of a sheet, said yieldable means will operatively engage said feed shelf for checking the movement of said sheet prior to the engagement of the forward edge thereof with said stops, a smoothing device operative upon the sheet while it is being fed from said feed shelf, said smoothing device being movable toward and from said feed shelf, and means whereby it is moved toward said feed shelf simultaneously with the movement of the front gauge stops away from the feed shelf, whereby said smoothing device is inoperative upon the sheet prior to its engagement with said front gauge stops and is made operative with relation thereto while a sheet is being withdrawn by the printing couple from said shelf.

45 12. A feeding mechanism for rotary printing machines embodying therein an inclined feed shelf section, front gauge stops co-operating therewith, means whereby said stops may be alternately interposed in the path of movement of the sheet upon said shelf, and removed therefrom, means for 50 checking the movement of said sheet prior to the engagement of the forward edge thereof with said stops, a shaft adjacent said stop gauges, a brush pivotally mounted upon said shaft, a torsion spring upon said shaft and operative upon said brush, to impart movement thereto away from said feed shelf, and means carried by the actuating means for said front gauge stops whereby said brush will be moved against the tension of said spring simultaneously with the raising of said stops.

55 13. A feeding mechanism for rotary printing machines embodying therein an inclined feed shelf section, a rock shaft mounted adjacent and above same, front gauge stops carried by said shaft, means actuated in synchronism with the printing couple whereby said shaft will be alternately lowered and raised so as to be interposed in the path of movement of a sheet upon said shelf, and will be removed from adjacent the shelf substantially simultaneously with the engagement of a sheet by the gripper mechanism upon the printing couple, means for checking the movement of said sheet prior to the engagement of the forward edge thereof with said stops, a shaft parallel with said first named shaft, a brush pivotally mounted upon said last named shaft, a torsion spring upon said shaft and operative upon said brush to impart movement thereto away from said feed shelf, stops carried by said brush and adapted to engage said first named shaft to limit the operative effect of said spring, tappets carried by said brush, and means carried by said first named shaft and adapted to engage said tappets, whereby with the actuation of said shaft carrying said front gauge stops, said brush will be permitted to have movement away from said feed shelf, and with the movement of said stop carrying shaft to move said stops away from said feed shelf, said brush will be moved toward said feed shelf.

60 14. A feeding mechanism for rotary printing machines embodying therein an inclined feed shelf section, a rock shaft mounted adjacent and above same, front gauge stops carried by said shaft, means actuated in synchronism with the printing couple whereby said shaft will be alternately lowered and raised so as to be interposed in the path of movement of a sheet upon said shelf, and will be removed from adjacent the shelf substantially simultaneously with the engagement of a sheet by the gripper mechanism upon the printing couple, means for checking the movement of said sheet prior to the engagement of the forward edge thereof with said stops, a shaft parallel with said first named shaft, a brush pivotally mounted upon said last named shaft, a torsion spring upon said shaft and operative upon said brush to impart movement thereto away from said feed shelf, stops carried by said brush and adapted to engage said first named shaft to limit the operative effect of said spring, tappets carried by said brush, and means carried by said first named shaft and adapted to engage said tappets, whereby with the actuation of said shaft carrying said front gauge stops, said brush will be permitted to have movement away from said feed shelf, and with the movement of said stop carrying shaft to move said stops away from said feed shelf, said brush will be moved toward said feed shelf.

65 15. A feeding mechanism for rotary printing machines embodying therein an inclined feed shelf section, front gauge stops co-operating therewith, means whereby said stops may be alternately interposed in the path of movement of the sheet upon said shelf, and removed therefrom, means for

to away from said feed shelf, stops carried by said brush and adapted to engage said first named shaft to limit the operative effect of said spring, tappets carried by said brush, ¹⁵ means carried by said first named shaft and adapted to engage said tappets, whereby with the actuation of said shaft carrying said front gauge stops, said brush will be permitted to have movement away from said feed shelf, and with the movement of said stop carrying shaft to move said stops away from said feed shelf, said brush will be moved toward said feed shelf, and adjustment means whereby the operative effect of said last named means may be varied to regulate the extent of movement of said brush toward or from said shelf.

In witness whereof I have hereunto affixed my signature, this 1st day of February, 1922.

FRANK C. MARQUARDT.
